Des. 226,464
Patented Mar. 13, 1973

226,464

MULTIPLE SEATING UNIT

Donald Michael Genaro, Haworth, N.J., John Niel McGarvey, Drexel Hill, Pa., and Frederick Allen Rosebrock, Greenfield, Ind., assignors to Bell Telephone Laboratories, Incorporated, Berkeley Heights, N.J.

Filed July 16, 1971, Ser. No. 163,557

Term of patent 14 years

Int. Cl. D6—02

U.S. Cl. D6—59

FIG. 1

FIG. 2

Des. 226,464

PAGE 2

FIG. 3

FIG. 4

FIG. 5

FIG. 6

FIG. 1 is an upper front perspective view of our novel design for a multiple seating unit adapted for wall mounting;

FIG. 2 is a lower front perspective view;

FIG. 3 is a top plan view;

FIG. 4 is a partial front elevation showing in enlarged detail the contour of the seat back;

FIG. 5 is an upper perspective view of a modified form of the design in which the seating unit is provided with a base for mounting on a floor; and

FIG. 6 is a lower front perspective view of the article taken slightly from the right in FIG. 5.

The undisclosed back portion is conventional in configuration.

We claim:

The ornamental design for a multiple seating unit, substantially as shown and described.
